Primary Examiner — Jae Liang(74) *Attorney, Agent, or Firm* — James A. Italia; Italia IP(57) **CLAIM**

The ornamental design for a molded glass cover, as shown and described.

DESCRIPTION

FIG. 1 is a perspective view of a molded glass cover showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken lines in the drawings depict environmental subject matter only and form no part of the claimed design.
